UNITED STATES PATENT OFFICE.

CONRAD FRIEDRICH GOTTFRIED, OF BROOKLYN, NEW YORK.

EAR AIR-DOUCHE.

1,323,466.

Specification of Letters Patent.

Patented Dec. 2, 1919.

Application filed September 25, 1918. Serial No. 255,682.

To all whom it may concern:

Be it known that I, CONRAD F. GOTTFRIED, a citizen of the United States, residing at Brooklyn, in the county of Kings and State 5 of New York, have invented certain new and useful Improvements in Ear Air-Douches; and I do hereby declare the following to be a full, clear, and exact description of the invention, such as will enable others skilled 10 in the art to which it appertains to make and use the same.

My invention relates to improvements in ear air douches.

An important object of this invention is 15 to provide an ear air douche adapted for use in connection with the treatment of different diseases of the ear resulting from explosions, loud noises, heavy bombardments and catarrh.

20 A further object of this invention is to provide an apparatus of the character described comprising a semi-bulbous shaped shell adapted to fit over the ear and prevent access of air to the ear other than the air 25 supplied by a medical air pump machine.

A further object of the invention is to 30 provide a douche of the character described comprising a semi-bulbous shaped shell having a centrally disposed tube adapted to extend into the earhole to convey the air from the medical air pump machine directly into the ear.

A further object of the invention is to 35 provide a douche of the character described comprising a semi-bulbous shaped shell and a centrally disposed air supply tube arranged therein, said bulbous shaped shell having a pair of exhaust apertures therein to permit of the exit of the air upon leaving the ear.

40 A further object of the invention is to provide a douche of the character described which may be used in conjunction with medical air pump machines or electro-medical 45 machines in the treatment of diseases of the ear.

Other objects and advantages of the invention will be apparent during the course of the following description.

50 In the accompanying drawing forming a part of this specification, and in which like numerals are employed to designate like parts throughout the same,

Figure 1 is a side elevation of a douche apparatus embodied in my invention, and

Fig. 2 is a central vertical longitudinal section taken through the same.

In the drawing, wherein for the purpose of illustration is shown the preferred embodiment of my invention, the numeral 5 designates a semi-bulbous shaped shell, which in manufacture may be of glass or any other desired material. The lower edge 5 of the semi-bulbous shaped shell 5 is provided with an outwardly extending annular flange 6, adapted to fit over the outside of the ear and effect an airtight engagement of the shell with the ear. Formed integral with the semi-bulbous shaped shell 5 and arranged on its outer face and centrally thereof is a cylindrical member 7, having a longitudinally extending axial opening 8. Formed integral with the cylindrical member 7, and alining with the axial opening 8, is a glass tube 9 having its forward end portion tapered, as at 10. A relatively small piece of flexible tubing 11 is adapted to be connected with the forward end portion 10 of the tube 9. The flexible tubing 11 is adapted to extend directly into the earhole 80 for the purpose of supplying air thereto during the process of the air treatment. Oppositely arranged exhaust apertures 12 are disposed in the sides of the shell 5, and are adapted to permit of the exit of the air 85 from the shell.

A collar or coupling 14 is adapted to be arranged over the cylindrical member 7, and has a tubular member 15 formed integral therewith. The tubular member 15 is in line 90 with the axial opening 8 of the cylindrical member 7. The tubular member 15 and the collar 14 are preferably of a metal and are adapted for connection with a medical air pump machine adapted to supply the 95 air to the ear during the douching process.

In the use of my improved douche apparatus, it will be apparent that the shell 5 is placed over the ear, thus effecting an airtight engagement. Practically simultaneous with 100 the application of the shell to the ear or head, the flexible tubing 11 is inserted into the earhole to convey the air directly to the point where it is most desired. The air is now supplied from the medical air pump 105 machine, and the process of douching the ear completed.

While I have shown and described the preferred embodiment of my invention, it is understood that I may make such minor 110

changes in construction and arrangement of parts, as will remain within the spirit of the invention and the scope of the appended claim.

5 Having thus described my invention, what I claim is:

An air ear douche including a glass shell having a centrally arranged cylindrical member provided with an axial opening, a
10 metallic coupling surrounding the cylindri-

cal member and having a reduced attaching tube, a glass tube formed integral with said cylindrical member, and a flexible tube connected to the glass tube.

In testimony whereof I affix my signature 15
in presence of two witnesses.

CONRAD FRIEDRICH GOTTFRIED.

Witnesses:

HEINRICH RENER,
EARL MILLER.
